[57] CLAIM

The ornamental design for a pin for locking or stopping a sliding window sash, as shown and described.

DESCRIPTION

FIG. 1 is a perspective view of a pin for locking or stopping a sliding window sash showing my new design;

FIG. 2 is a rear elevational view thereof;
FIG. 3 is a side elevational view thereof, the opposite side being a mirror image;

FIG. 4 is a front elevational view thereof;

FIG. 5 is a top plan view thereof; and,

FIG. 6 is a bottom plan view thereof.

FIG. 1

FIG. 5

FIG. 6

FIG. 2

FIG. 3

FIG. 4
